(57) **CLAIM**

The ornamental design for a sling for archery bow, as shown and described.

DESCRIPTION

FIG. 1 is a perspective view of the sling for archery bow, in accordance with the present invention;

FIG. 2 is a front elevation view of the embodiment shown in FIG. 1;

FIG. 3 is a rear elevation view of the embodiment shown in FIG. 1;

FIG. 4 is a right side elevation view of the embodiment shown in FIG. 1, the left side being a mirror image thereof; and,

FIG. 5 is a top plan view of the embodiment shown in FIG. 1. The archery bow depicted in FIG. 1 shown in broken line for environmental purposes only and as such forms no part of the claimed invention.
